DESIGN.

P. S. KEPLER.
BIAS STICK.

No. 27,924.

Patented Nov. 30, 1897.

Inventor

Porteus S. Kepler

Witnesses

L.R. Medcalf
D.P. Thompson

By his Attorneys,

C. Snow & Co.

UNITED STATES PATENT OFFICE.

PORTEUS S. KEPLER, OF ASHTABULA, OHIO.

DESIGN FOR A BIAS-STICK.

SPECIFICATION forming part of Design No. 27,924, dated November 30, 1897.

Application filed September 2, 1897. Serial No. 650,404. Term of patent 14 years.

To all whom it may concern:

Be it known that I, PORTEUS S. KEPLER, a citizen of the United States, residing at Ashtabula, in the county of Ashtabula and State of Ohio, have invented a new and original Design for a Bias-Stick for Marking, of which the following is a specification.

This invention relates to a new and original design for a bias-stick for marking; and it has for its object to provide a design of this character that shall be both useful and ornamental.

The leading feature of the design resides in a pair of equal-length straight flat strips joined together at one end and arranged at right angles to each other and a straight flat hypotenuse strip lying across the angle between the right-angularly-disposed strips and connecting the extremities of the latter, said hypotenuse strip having a straight continuation or extension projecting beyond one of the right-angularly-disposed strips at an obtuse angle thereto.

In the drawings, Figure 1 is a perspective view of a bias-stick embodying the herein-described design. Fig. 2 is a plan view thereof.

Referring to the drawings, the numerals 1 and 2 designate a pair of equal-length straight flat strips arranged at right angles to each other and joined together at one end, the other ends or extremities of said strips being connected by a straight flat hypotenuse strip 3. The hypotenuse strip 3 lies across the angle between the strips 1 and 2 and is provided with a straight continuation or extension 4, which projects beyond the strip designated by the numeral 1 and is disposed at an obtuse angle to such strip.

What I claim is—

The design for a bias-stick herein shown and described.

In testimony that I claim the foregoing as my own I have hereto affixed my signature in the presence of two witnesses.

PORTEUS S. KEPLER.

Witnesses:

A. P. LAUGHLIN,
JOHN J. MURPHY.